United States Patent

Des. 237,155
Patented Oct. 14, 1975

237,155

BICYCLE REFLECTOR

Frank P. Brilando and Rudolph L. Schwinn, Niles, Ill.,
assignors to Schwinn Bicycle Company, Chicago, Ill.

Filed Mar. 29, 1974, Ser. No. 456,356

Term of patent 14 years

Int. Cl. D10—06

U.S. Cl. D10—111

Fig. 1.

Fig. 3.

Fig. 2.

Fig. 4.

Fig. 5.

FIG. 1 is a front view of a bicycle reflector showing our new design;

FIGS. 2 and 3 are bottom and side views, respectively, of FIG. 1; and

FIGS. 4 and 5 are front rear perspective views of the bicycle reflector.

We claim:

The ornamental design for a bicycle reflector, substantially as shown and described.
